PIERCING PUNCH

Robert A. Gargrave, Dayton, Ohio, assignor to Dayton Perforators, Inc., Dayton, Ohio, a corporation of Ohio

Application November 21, 1955, Serial No. 548,044

4 Claims. (Cl. 83—128)

This invention relates to piercing punch assemblies, and particularly to such assemblies in which an ejector pin is extensible relatively to the punch element to dislodge cut blanks which might adhere to the work engaging face thereof.

The object of the invention is to simplify the construction as well as the means and mode of operation of piercing punch assemblies, whereby such assemblies may not only be economically manufactured, but will be more efficient and satisfactory in use, adaptable to a wide variety of applications, and be unlikely to get out of repair.

A further object of the invention is to obviate the need for a general dismantling of the punch assembly, equipped with an ejector mechanism as described, in preparation for grinding the work face.

Another object of the invention is to enable retraction of the ejector pin in a punch assembly as described and the holding of the pin in retracted position without the necessity of gaining access to both ends of the punch element.

A further object of the invention is to enable the ejector pin to be ground off in conjunction with and to a corresponding extent as the work engaging face of the punch element.

A further object of the invention is to provide a piercing punch assembly possessing the advantageous structural features, the inherent meritorious characteristics and the mode of operation herein mentioned.

With the above primary and other incidental objects in view as will more fully appear in the specification, the invention intended to be protected by letters patent consists of the features of construction, the parts and combinations thereof, and the mode of operation as hereinafter described or illustrated in the accompanying drawings, or their equivalents.

Referring to the accompanying drawing wherein is shown one but obviously not necessarily the only form of embodiment of the invention,

Fig. 1 is a view in longitudinal section, partly diagrammatic, of a piercing punch assembly in accordance with the illustrated embodiment of the invention;

Fig. 2 is a view of the punch element and holding means therefor, of Fig. 1, shown in larger scale and in position for grinding of the work engaging face;

Fig. 3 is a fragmentary view in longitudinal section of the punch element showing one location for a lateral opening in the punch element, forming a part of the instant invention; and

Fig. 4 is a view similar to Fig. 3 showing a different location for such opening.

Like parts are indicated by similar characters of reference throughout the several views.

Referring to the drawings, a piercing punch assembly of a kind to which the instant invention may be applied comprises a punch holder 10 and a punch pad 11 in parallel interconnected relation. In aligned spaced apart relation to the holder 10 and pad 11 is a die block 12

2

receiving an insert die 13 and backed up on its under side by a die holder 14. Disposed between the punch pad 11 and the die block 12 is a stripper member 15. The pad 11 is provided with a bore 16 and a counterbore 17 receiving a punch element 18, the latter having a barrel portion 19 fitting closely within the bore 16 and a head 21 received in the counterbore 17 and limiting outward or downward thrust of the punch element relatively to the pad. The holder 10 backs up the pad 11 and prevents rearward withdrawing motion of the element 18.

10 The barrel 19 of the element 18 terminates in a reduced diameter portion 22 axially aligned with an opening 23 in the stripper member 15 and with the interior of die insert 13. According to the mode of operation of assemblies of the kind described, a stock material 24 is fed across the die block 12 while the separate assemblies 10—11 and 12—14 reciprocate relatively to one another. In response to such motion, the nose 22 of the punch element 18 passes through the opening 23 in stripper plate 15 and engages the stock 24, continued approaching motion of

15 the assemblies as described resulting in a part of the stock being cut out of the material thereof, corresponding in size to the interior of the die insert 13, the blank thus defined dropping downward through the insert 13 and out of the punch assembly by way of an opening 25 in the die holder 14. The lower end of the nose portion 22 of the punch element may be considered to define a work engaging surface or face 26 and it will be understood that for proper quality of work, this surface must be kept planar and the edges thereof kept sharp. It is necessary periodically to grind the work surface or face to maintain it in a good operating condition against the effects of wear.

20 The punch element passes through the stock 24 in cutting a blank therefrom and on the retracting stroke of the punch element the stripper member or plate 15 is effective to restrain the stock from following the punch element. It may occur that the cut blank, instead of dropping out of the assembly will tend to adhere to the work face 26 during withdrawal or retraction of the punch element. To obviate this occurrence, the punch element is formed with a longitudinal through bore 27 in which there is an ejector pin 28 adapted to extend through and beyond the work face 26 to positively remove an adhering blank 29 therefrom.

25 The bore 27 terminates at its inner or upper end in a counterbore 29 in which is a head 31 integral with the pin 28. A compression spring 32 also is in the counterbore 29, interposed between the head 31 and a screw stud 33 installed in the outer end of the counterbore in the head 21 of the punch element. The pin 28 is thrust downward or outward by the spring 32 and the parts are so proportioned that with the head 31 of the pin limiting in the bottom of counterbore 29 a predetermined part of the length of the pin 28 projects through and beyond the face 26. The spring 32 is relatively light and yields when the projecting part of the pin 28 contacts the stock 24. By the reactant pressure of the stock 24, therefore, the pin 28 is retracted into the bore 27 during the downward or cutting stroke of the punch so that the ejector pin is in effect merely a part of the punch element. When the reactant pressure of the stock 24 is removed, however, after cutting of the blank therefrom, the spring 32 is released and thrusts the ejector pin 28 outward to the position shown in Fig. 1 and any tendency of the blank to adhere to the face 26 accordingly is overcome.

30 The barrel 19 of the punch element 18 is formed, at the bottom of counterbore 28, with a lateral opening 34 in intersecting or communicating relation to the counterbore 29. The opening 34 is predetermined in size to admit thereto a selective stop for the pin 28, as a cotter pin

35 40 45 50 55 60 65 70

35 as seen in Fig. 2. Thus, in a nonoperating position of the parts, the ejector pin 28 may be pressed by hand to a retracted position as indicated in Fig. 2, and the cotter pin 35 or like device inserted in the opening 34 in position to underlie the head 31 on the ejector pin. The ejector pin is by this means locked in a retracted position. As shown in Fig. 3, the opening 34 may be radial with respect to the axis of counterbore 29 or, as shown in Fig. 4, it may take the form of an opening 36 non-radial with respect to the axis of the counterbore. In either case, an insert member such as the cotter pin 35 will underlie the head of the ejector pin and lock it as described in retracted position.

The instant described construction and arrangement of parts makes possible grinding of the face 26 of the punch element without removal of the punch element from the pad 11 and holder 19. Thus, while the punch element, punch pad and punch holder are still assembled they may be inverted from their normal working position and the work face 26 applied to the surface of a grinding wheel or the like. The size of opening 34 or 36 and of the stop member 35 to be inserted therein may in this connection be predetermined to define a retracted position for the ejector pin which places the outer end thereof in the plane of the face 26. Accordingly, as the face 26 is ground the outer end of the pin 28 also is ground and the same relative position of the parts at all times is in this way preserved.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect, and the invention is therefore claimed in any of its forms or modifications within the legitimate and valid scope of the appended claims.

Having thus described my invention, I claim:

1. A piercing punch including a punch element having a working face and a longitudinal bore through said face, a counter bore aligned with said bore through the end 5 of the punch opposite said working face, a shoulder formed by said counter bore, a headed ejector pin received in said bore and said counter bore with the head of the pin normally engaging said shoulder, spring means urging said pin outwardly to project the outer end thereof from said bore through and beyond the working face of the punch element, the working face of the punch element and the face of the ejector pin being both plane surfaces, said surfaces being at right angles to the axis of the bore within said punch element, an opening through the wall 10 of said punch into said counter bore adjacent said shoulder and means selectively installed in said opening for holding said pin in a retracted position with the outer end thereof in the plane of said working face on said punch element for unison grinding of said working face 15 and said pin.
2. The structure according to claim 1, having means inserted in the counter bore for adjusting the tension on the spring urging the pin outwardly from the end of the punch.
- 25 3. The structure according to claim 1, wherein the opening through the wall of the punch intersects the axis of the counter bore.
4. The structure according to claim 1, wherein the opening in the punch is offset from the axis of the counter bore and substantially tangent to the surface of the bore.
